UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,932, dated May 16, 1882.

Application filed March 16, 1882. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is shown in the accompanying photographic illustration.

The chief features of my design are, first, a large bouquet, A, composed of flowers, foliage, and a sheaf of wheat; second, a bouquet, B, contained in a vase, C; third, a smaller sheaf of wheat, D; fourth, a slender plant, E, with leaves and blossoms; and, fifth, borders, blocks, and scroll-work ornamenting the ground of the carpet.

I claim —

The design for a carpet, substantially as shown and described.

In testimony whereof I have signed my name to this specification, in the presence of two subscribing witnesses, this 9th day of March, 1882.

THOMAS J. STEARNS.
